UNITED STATES PATENT OFFICE.

ABRAHAM ASHKENAS, OF BROOKLYN, NEW YORK.

DESIGN FOR A SCREEN.

Application filed February 1, 1928. Serial No. 25,125. Term of patent 14 years.

To all whom it may concern:

Be it known that I, ABRAHAM ASHKENAS, and a citizen of Austria, residing at Brooklyn, in the county of Kings and State of New York, have invented a new, original, and ornamental Design for a Screen, of which the following is a specification, reference being had to the accompanying drawing, forming a part thereof.

Fig. 2 is a top plan view thereof.

I claim:

The ornamental design for a screen, as shown.

ABRAHAM ASHKENAS.
